UNITED STATES PATENT OFFICE

2,551,246

FLUID MOTOR

Alfred C. D'Arcey, Norwood, Mass., assignor to
 Bendix Aviation Corporation, Norwood, Mass.,
 a corporation of Delaware

Application January 30, 1946, Serial No. 644,287

2 Claims. (Cl. 121—38)

1

This invention relates to fluid motors, and particularly to fluid motors of the servo-type, in which each energization of the motor is for the purpose of moving a work performing element from one to another of its several pre-determined settings—as, for example, the forward, reverse, or neutral position of a clutch or reversing gear.

An object of the invention is to provide a multiple position motor of novel construction, featuring simplicity of arrangement and a minimum number of parts.

Another object is to provide a multiple position motor whose parts are so inter-related as to assure positive action of accurate extent in moving from one position to another, as desired.

Another object is to provide a motor in which accurate positioning is accomplished without resorting to the use of complicated indexing or latching mechanism.

These and other objects of the invention will become more apparent upon reading the following detailed description of the presently preferred embodiment of the invention, as illustrated in the accompanying drawings. It is to be understood, of course, that the drawings are illustrative only, as the invention embraces other embodiments within the scope of the appended claims.

In the drawings, Figure 1 is a schematic representation of a hydraulic system embodying the present invention;

Figure 2 is a sectional view on a larger scale, showing the moving parts in the positions assumed when the device to be actuated is in one of its three possible settings; and

Figures 3 and 4 are views similar to Figure 2, 35 but showing two other possible settings.

Referring to these drawings, wherein like reference characters designate the same part throughout the several views, the characters 10 and 11 designate a pair of cylinders disposed in tandem relationship, with the smaller cylinder 11 integrated with or rigidly secured to the larger cylinder 10, so that the two have a common dividing wall 12 through which there extends a hollow tube or rod 13 carrying at one end a piston 14 and at the other end one or more stop elements 15, 16 threaded to the threaded end portion of the rod 13, for a purpose to be more fully explained. A second piston, 18, is slideable in the larger cylinder 10, and is integrated with a 50 rod 19 extending through the outer wall 20 of the larger cylinder and having operative connection with the device 21 to be actuated. Such device 21 may be the reversing gear of a marine engine, or any other power or directional control

2

that is shiftable to any one of a plurality of settings.

Three-way valves 31, 32, 33 (Figure 1) control flow of fluid to and from ports 34, 35, 36, of the cylinders 10 and 11; the pump for the fluid being indicated at 41 in Figure 1, and the reservoir at 42.

For the ahead, or most extended position of the rod 19 (Figure 4), hydraulic pressure is applied to ports 35 and 36, which pressure acts on the back or reverse faces of pistons 14 and 18. This pressure drives piston 18 to its extreme or full ahead position and also drives piston 14 forward until the locknut or adjusting nut hits the 15 partition 12 between the two cavities of the cylinders. This latter operation performs no useful function except to put piston 14 in position for the next operation or hold it in place from the preceding operation (Figure 3).

20 To go into the neutral or mid position (Figure 3) pressure is applied to ports 34 and 35 and relieved at port 36. The pressure entering port 34 acts on the front or ahead face of piston 18 driving it in the reverse direction. The fluid 25 trapped between pistons 14 and 18 is exhausted through the central bore in the rod 13, then out through port 36, permitting piston 18 to come up against piston 14; piston 14 then restricts further movement of piston 18 by virtue of the fact 15 that although the forward face of piston 14 and the rear face of piston 18 are subject to the same fluid pressure, the rod of piston 18 is larger in diameter than the rod of piston 14 and consequently presents less effective area to the pressure exerted, and therefore less force.

The piston rod of piston 14 extends through a partition 12. Carried on the end of the piston rod are the adjustable nuts 15, 16, the purpose of which is to adjustably limit the most forward or ahead position of piston 14, thus making adjustable the mid or neutral position of the device.

To go into the reverse, or least extended, position of the cylinder fluid pressure is applied to port 34 and exhausted from ports 35 and 36. This permits the pressure on the front or ahead face of piston 18 to drive it and piston 14 into the reverse or astern position (Figure 2).

To go into the mid or neutral position again fluid pressure is applied through ports 34 and 35. The differential area in favor of piston 14 previously mentioned permits it to drive in the forward or ahead direction, forcing piston 18 along with it despite the fact that the same fluid 55 pressure may be exerted on the forward or ahead

face of piston 18. Piston 14 will continue to move forward until the adjustable nut 16 hits the face of the cylinder partition 12, thus limiting further movement of piston 14 and consequently 18.

Thus, the manner in which fluid pressure is admitted and exhausted from the 3 ports of the cylinder determines the direction of motion and ultimate position of the piston rod of piston 18, from which motion power can be taken for the 10 purpose of operating a marine reverse gear 26, or performing any other function where three positive positions are required.

The valves 31, 32, and 33 may be operated directly, or by remote control, as by electric 15 switches in the circuits leading to the solenoid windings of the valves; if the valves are of a solenoid type.

A by-pass valve, for pressure relief purposes, may be inserted across lines 62 and 63, as indicated at 64. Also, a filter 64 may be inserted in return line 63 for fluid cleaning purposes.

Where specific speed or power differentials are desired, in moving from one predetermined position to another, these can be obtained by use of the concept disclosed therein of providing differential effective areas on opposite sides of the piston 18. By varying the degree of difference in these respective areas, any desired ratio of power differential may be effected.

What is claimed is:

1. In a device of the class described, a pair of cylinders in tandem relationship having a common end wall, a pair of pistons arranged end to end in one of said cylinders, a hollow rod connected to one of the pistons and extending through said common end wall into the other cylinder so as to communicate the space formed in said one cylinder between the adjacent ends of said piston with the other cylinder, an adjustable element carried by said rod for engagement with said common end wall to limit the movement of said one piston in one direction, said other piston adapted to be connected to a member for moving the same to three positions, means for connecting one end of said one cylinder to a fluid pressure source and the other end of said one cylinder and said other cylinder to exhaust to cause said other piston to assume one position, means for connecting both ends of said one cylinder to said source and said

other cylinder to exhaust to cause said other piston to assume a second position, and means for connecting said one end of said one cylinder to exhaust and said other end of said one cylinder and said other cylinder to said source to cause said other piston to assume a third position.

2. In a device of the class described, a pair of cylinders in tandem relationship having a common end wall, a pair of pistons arranged end to end in one of said cylinders, a hollow rod connected to one of the pistons and extending through said common end wall into the other cylinder so as to communicate the space formed in said one cylinder between the adjacent ends of said piston with the other cylinder, an adjustable element carried by said rod for engagement with said common end wall to limit the movement of said one piston in one direction, said other piston adapted to be connected to a member for moving the same to three positions, the effective areas of the adjacent ends of the pistons being equal and the effective areas of the remote end of said one piston being greater than the effective area of the remote end of said other piston, means for connecting one end of said one cylinder to a fluid pressure source and the other end of said one cylinder and said other cylinder to exhaust to cause said other piston to assume one position, means for connecting both ends of said one cylinder to said source and said other cylinder to exhaust to cause said other piston to assume a second position, and means for connecting said one end of said one cylinder to exhaust and said other end of said one cylinder and said other cylinder to said source to cause said other piston to assume a third position.

ALFRED C. D'ARCEY.
